UNITED STATES PATENT OFFICE.

JOHN H. COUGHLIN, OF CLINTON, MASSACHUSETTS.

METHOD OF PACKAGING BREAKABLE ARTICLES.

Application filed April 16, 1924. Serial No. 706,849.

My present invention relates to an improved method of packaging breakable articles.

One of the serious problems of present day merchandising is the proper packaging of articles, and particularly the proper packaging of breakable articles such as glass containers. Where the size of the package is to be smaller than the wholesale shipping unit, no method of packaging of which I am aware will properly take care of the problem of preventing excessive breakage. Particularly is this true with regard to beverages held in glass bottles and the like which it is usual to package in a unit size of approximately one half dozen bottles. The commercial wholesale way of packaging such articles so as to insure safe transit and prevent breakage is in cases of wood or steel arranged with compartments to hold on an average twenty four bottles. In retailing such bottles, however, the commercial container is too large as the average unit retailed in the small shop is six bottles. Due to the small size of the unit and the relatively small margin of profit in handling goods of this class, no expensive container can be commercially successfully employed. Of late, a small unit corrugated container has been brought on the market which is admirably adapted to hold the usual retail commercial unit, but the breakage in utilizing such unit has been found to be excessive. Attempts to place within such low priced and cheap material container a separating element have been tried, but unsuccessfully, due to the cost. As beverages, particularly in bottles, are sold direct to consumers and a large proportion of such sales are made to people on picnics, outings, or the like, and as such people are not ordinarily equipped with drinking receptacles and as a great many people object to drinking directly from a bottle, I have devised a method for packaging bottles containing liquid such as beverages and the like, and utilize as separating devices the modern form of sanitary paper drinking cups. In practicing my invention I place on each bottle a paper drinking cup which therefore acts not only as a means for holding such bottle away from an adjacent bottle, but also acts to preserve free from dirt, dust, and the like the upper portion of the bottle.

The object of my invention, therefore, is an improved method of packaging breakable articles.

In the accompanying drawings illustrating a plurality of breakable articles arranged in a container according to my invention,

Fig. 1 is a sectional elevation through a container showing the bottles with the drinking cups in position thereon;

Fig. 2 is a plan view of Fig. 1 with the cover of the container removed, and

Fig. 3 is an enlarged sectional detail on the line 3—3 of Fig. 2.

Referring to the drawings, 10 designates a container of corrugated paper or other suitable material provided with a cover 11 of like material adapted to be placed thereon, or folded over so as to enclose the articles in the container. The container 10 is of such dimensions as to allow a proper number of bottles 12 or other containers to be placed therein in ranked formation and on each of the bottles is placed a paper sanitary drinking cup or similar article 13. Such drinking cup is preferably of that type wherein the drinking edge is rolled, as at 14, such roll edge performing the double function of obviating a sharp edge on the cup and also tending to make such cup more rigid. The roll edge 14 being of substantial size and the depth or height of the cup 13 being such, with respect to the body of the bottle 12, as to extend to a point 15 where the body portion of the bottle merges into the neck portion thereof, such roll edges 14 engage with each other, as shown in Fig. 3, and hold the bottles 12 positively separated from each other. Such roll edges 14 act as, and perform the part of, a separating member located between adjacent bottles and the roll edges engaging with each other prevent the force attending sudden jars from being transmitted to the bottles themselves. There is, therefore, no direct contact of the bottles 12 one with the other and, therefore, I have found that the breakage is reduced to a minimum. The cups 13 being equal in number to the number of bottles 12 in the container 10, each individual bottle is associated with a drinking cup so that the purchaser of the unit may dispense a bottle and a cup to each person using the same. This idea further carries out the modern idea of sanitary

drinking of liquids in that the members of a party are not obliged, as heretofore, to utilize a common drinking cup.

My method of packing is applicable to other articles of breakable nature besides beverage-containing bottles, but as my invention was designed particularly for this purpose, I have illustrated it in connection with the beverage containing bottle. It is 10 to be understood, however, that I am not to be limited to the particular type of bottle employed other than as pointed out in the appended claim.

Having thus described my invention, what 15 I claim as new is:

That improvement in the art of packaging breakable articles which consists in utilizing a container adapted to hold a predetermined number of bottles in ranked formation, fitting each bottle with an individual drinking cup to enclose and protect the mouth of such bottle, and utilizing such individual drinking cup as a protecting and separating device to hold each individual bottle separate and out of actual contact with adjacent 20 bottles.

In testimony whereof, I have signed my name to this specification.

JOHN H. COUGHLIN.
